DISPLAY FIXTURE

Edwin C. Parrotte, Coral Gables, Fla., assignor to
Golf, Inc., Miami Springs, Fla.

Filed June 14, 1971, Ser. No. 152,932

Term of patent 14 years

Int. Cl. D6—04

U.S. Cl. D6—186

FIG. 1

FIG. 2

FIG. 3

FIG. 4

FIG. 5

FIG. 6

FIG. 7

FIG. 8

FIG. 10

FIG. 1 is a front elevation view of a display fixture in accordance with the present invention;

FIG. 2 is a left side elevation view thereof;

FIG. 3 is a top plan view thereof;

FIG. 4 is a bottom plan view thereof;

FIG. 5 is a rear view thereof;

FIG. 6 is a front elevation view of a display fixture in accordance with another embodiment of the present invention;

FIG. 7 is a left side elevation view thereof;

FIG. 8 is a top plan view thereof;

FIG. 9 is a bottom plan view thereof; and

FIG. 10 is a rear view thereof.

Each right side elevation view is a mirror image of its respective left side elevation view.

I claim:

The ornamental design for a display fixture, substantially, as shown and described.
